[57] CLAIM

The ornamental design for a magnetic optical disc
drive, as shown and described.

DESCRIPTION

FIG. 1 is a perspective view of a magnetic optical disc
drive showing my new design;

FIG. 2 is a front view thereof;

FIG. 3 is a rear view thereof;

FIG. 4 is a right side view thereof the left side view
being a mirror image;

FIG. 5 is a top view thereof; and,

FIG. 6 is a cross sectional view thereof taken along line
VI-VI of FIG. 2.

FIG. 2**FIG. 3****FIG. 4****FIG. 5**

FIG. 6
